UNITED STATES PATENT OFFICE.

HUDSON MAXIM, OF LONDON, ENGLAND.

AUTOMOBILE TORPEDO.

SPECIFICATION forming part of Letters Patent No. 641,787, dated January 23, 1900.

Application filed February 12, 1898. Serial No. 670,041. (No model.)

To all whom it may concern:

Be it known that I, HUDSON MAXIM, a citizen of the United States of America, residing at 377 Norwood road, London, S. E., England, have invented certain new and useful Improvements in Automobile Torpedoes, of which the following is a specification.

My invention relates to torpedoes, and more particularly to that class of torpedoes which possess within themselves the means required for their propulsion and known in the art as "automobile" torpedoes. Such torpedoes have heretofore been constructed with a reservoir for any suitable motive fluid, as compressed air, which fluid is utilized for driving a propeller. In order that such torpedo might have sufficient power stored in the reservoir to drive it at the desired speed or to the required distance, or both, it has heretofore been found necessary to construct the reservoir of such size as to occupy the greater portion of the space within the torpedo, thereby greatly restricting the space to be utilized in carrying the explosive charge. In order to carry an explosive charge of even moderate efficiency, it has been found necessary to considerably encroach upon the space needed for the motive apparatus, thereby greatly lessening the efficiency and accuracy of the torpedo.

The object of the present invention is to construct a torpedo which within a shell of given proportions shall be capable of carrying a much larger explosive charge than has heretofore been practicable and also be able to travel at a greater speed and for a greater distance than has heretofore been deemed possible in this class of torpedoes.

With these objects in view the invention consists in a torpedo having a suitable chamber therein for the explosive charge and a suitable motive fluid contained in a reservoir which is provided with means for supporting and burning a suitable combustible nitro compound in such a manner that the products of combustion may combine with or enter with the motive fluid into the torpedo-motor, so that not only is the pressure of the motive fluid increased or maintained for a longer period of time and its volume augmented, but the air is so heated that it will not freeze or produce appreciable cold, and thus hinder the proper operation of the motor. In its pre-

ferred form a chamber containing a suitable liquid, as water, is connected with the motive-fluid reservoir by means of a passage controlled by a valve opening toward fluid-pressure in the reservoir, and the combustible nitro compound is supported and burned in such manner that the products of combustion therefrom will mix with the liquid in the chamber, thereby raising its temperature and increasing its pressure sufficient to overcome the pressure of the fluid in the reservoir on the valve in the connecting-passage, so that the heated or vaporized liquid and products of combustion will pass from the liquid-chamber into the reservoir and mix with the motive fluid therein. The motive fluid is conducted by a suitable conduit to the motor, which may be of any preferred type, and in its most approved form the vaporized liquid and products of combustion from the chamber containing the water or other liquid are mixed with the motive fluid at a point in close proximity to the mouth of the conduit leading from the reservoir to the motor.

In the accompanying drawings I have shown for the purpose of illustration certain forms which my invention may assume; but it is to be understood that in so doing I do not mean thereby to define the limits of the invention, as the same inventive idea may be expressed in various forms.

In said drawings, Figure 1 is a longitudinal vertical section of one form of my new torpedo, parts at the front and rear being broken away. Fig. 2 is a similar view of a modified form of the torpedo, and Fig. 3 is a view of another modification.

Referring first to Fig. 1 of the drawings, in which like letters refer to like parts throughout the several views, the chamber for the explosive charge is indicated by the letter A, said chamber being, as usual, in the forward or bow end of the torpedo, and B indicates the reservoir for motive fluid, which is preferably compressed air, having the pipe C leading therefrom to the motor, (not shown,) which pipe C is controlled by a suitable valve, as c. Supported within the reservoir B is the combustion-chamber, which in this instance is in the form of a tube D, centrally and longitudinally arranged with respect to the motive-fluid reservoir and preferably extending be-

between the two heads of the reservoir and supported in any proper manner thereby. This tube contains the combustible nitro compound E, and near one end—in Figs. 1 and 3 the rear end—the walls of the tube just rear of the charge are perforated, so as to permit the products of combustion to pass from the tube E to the reservoir.

In order that the heat of the products of combustion may be more thoroughly utilized to prevent the freezing of the air in its expansion, it is preferred to surround the perforated walls of the tube with a jacket d, (see Figs. 1 and 3,) terminating in a mouth or nozzle e, located near the delivery-pipe C, so that the hot products of combustion will be directed into and become mixed with that portion of the air which is about to be expanded in performing its duty. At the same time that the air is prevented from freezing it necessarily results that the temperature of the products of combustion are considerably lowered, so that they can be safely utilized as a motive fluid or as a part of a motive fluid without danger to the motor or its connections.

In addition to the advantages heretofore enumerated incident to the use of the combustible charge it will be obvious that in addition to the usual volume of compressed air with which the chamber will be charged the combustible charge will in itself provide an exceedingly large volume of gas to augment the air charge and also largely increase the pressure of the motive fluid passing to the motor, and hence the invention in this important particular renders it possible to largely increase the charge in a self-propelling torpedo, in which up to the present time the explosive charge has been restricted in weight by reason of the space necessarily taken up by the compressed-air chamber, which must contain a sufficient volume to drive the torpedo the maximum distance. At the same time also the size of the compressed-air chamber has been restricted, because of the need of carrying a sufficient explosive charge to insure the torpedo doing effective work, and hence the distance to which the torpedo could be driven has been also limited. By reason of the present invention, however, it is possible without any increase in size thereof and without diminishing the weight of the explosive charge to provide the torpedo with means for evolving a large volume of comparatively high pressure gases only generated as fast as needed and which in addition to augmenting the volume of the compressed-air charge also serves by their heat to prevent the air from freezing.

Any desired means may be employed for igniting the combustible charge at the desired moment. As shown, the charge will be ignited by an electric current in circuit with the wires f, leading to the rear end of the charge. The generator F, by which the necessary incandescence or spark is formed to ignite the charge, may obviously be connected

to or form part of the propelling-motor of the torpedo, so that the instant after the motor starts, due to the passage of the compressed air thereto, sufficient electricity will be generated to fire the combustible charge, so that it will thereupon commence to evolve the necessary heated gases to mingle with the compressed air, as before described.

In order that there may be no danger of the combustible charge going out at its initial ignition, a small piece of wick or other highly inflammable material i may be inserted in the end of the charge E, so that simultaneous with the ignition of the charge the wick will burn and will continue to burn until such time as there is no longer any danger of the charge blowing out.

In the form of the invention shown in Fig. 2 the torpedo having the air-chamber B is provided with a water-chamber G, with which water-chamber is arranged a combustion-chamber D', its forward end opening into the water-chamber and provided with a combustible charge E' of the character before referred to. From the water-chamber and extending through the air-chamber B there is provided a conical tube H, with its rear and smaller open end in line with the delivery-pipe C, leading to the motor. The water end of this conical tube is controlled by any suitable valve g, held to its seat to prevent the accidental escape of the water from the chamber G by the air-pressure which is normally in said tube. When the combustible charge E' is ignited, as by the electric current in the circuit f, the products of combustion will enter the water of the chamber G, increase its pressure, and raise its temperature sufficient to overcome the air-pressure against the valve g, so that the heated or vaporized water and the products of combustion will pass through said tube into the delivery-pipe C to mix with the air passing through said pipe to the motor. In thus mixing the heated or vaporized water and products of combustion with the air the temperature of the air will be raised sufficient to prevent it from freezing and the volume of gases passing through the motor will be increased.

In the form of the invention shown in Fig. 3 substantially the structure shown in Fig. 1 is adopted, with the addition of the water-chamber G and combustion-chamber D' of Fig. 2. In this instance, however, the combustible charge E is perforated longitudinally to receive an atomizing-tube h, leading from the water-chamber to the rear end of said charge. Upon the ignition of the combustible charge in the chamber D' and the accumulation of the products of combustion in the water-chamber the pressure thus generated will overcome the air-pressure upon the check-valve g' in said tube h and will atomize the water in forcing it through said tube. The atomized water, with the products of combustion, will be delivered at the rear end of the combustion-chamber D and will pass, with

the products of combustion, from the combustible charge E therein into the air-chamber, and thence out by the delivery-pipe C to the motor. The means for igniting the two charges E E' in this example of the invention may obviously be the same as that before described.

The forward head of the air-chamber B may be provided with a valve k, held seated by the air-pressure therein, which, should the pressure in the water-chamber G become unduly great and overbalance that in the air-chamber, will open to allow the contents of the chamber G to vent directly into the air-chamber. A similar valve may be of course provided in the structure shown in Fig. 2, for a similar purpose.

While I have referred to the chambers B and G as being respectively an air or compressed-air chamber and a water-chamber, it is to be understood that any other suitable fluid is intended to be covered thereby—such, for instance, as carbonic-acid gas, liquid hydrocarbons, solutions of ammoniacal gas, and the like.

Of course it will also be understood that when the water-chamber G is employed sufficient air-space should be left in such chamber to provide for the reception of the products of combustion which are to exert their elastic force in expelling the water outward toward the motor, so that dangerous pressures shall not be generated, owing to the too close confinement of the explosive.

35 What I claim is—

1. In an automobile torpedo a shell or hull having a chamber for the explosive charge, a reservoir containing a motive fluid, with a pipe

or conduit leading therefrom to the motor, a solid combustible charge, a passage-way for 40 the gases of combustion from said charge to the reservoir, and means for igniting said charge.

2. In an automobile torpedo, a shell or hull having a chamber for the explosive charge, a 45 reservoir for the motive fluid, with a pipe or conduit leading therefrom to the motor, a combustion-chamber within said reservoir, a combustible nitro compound in said chamber, a passage for the gases of combustion 50 from said combustion-chamber to said reservoir and means for igniting said nitro compound.

3. A self-propelling torpedo provided with a chamber for an explosive charge, a compressed-air reservoir, a water-chamber, a combustible charge having communication with said water-chamber, and thence with the air-chamber, means for igniting the combustible charge, and a conduit leading from the 55 reservoir to the motor.

4. A self-propelling torpedo provided with a chamber for an explosive charge, a reservoir for motive fluid, a water-chamber, two combustible charges, one communicating with 60 the reservoir and one with the chamber, means for igniting said charges, and means commingling the gases of combustion with the motive fluid and conducting the same to the motor.

In witness whereof I have hereunto set my hand in the presence of two witnesses.

HUDSON MAXIM.
